METERING MECHANISM

Riccard Pudelko, Zug, Switzerland, assignor to
Landis & Gyr, A.-G., a corporation of Switzerland

Application October 16, 1935, Serial No. 45,203
In Switzerland October 17, 1934

4 Claims. (Cl. 194—90)

The invention relates to new and useful improvements in coin controlled mechanisms, and more especially to such improvements in coin controlled electricity meters.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Fig. 1 is a diagrammatic view of a mechanism embodying the invention; and

Fig. 2 is a diagrammatic view of a different form of mechanism embodying the invention.

25 Objects of the invention are, in part, to provide an improved and simplified coin controlled mechanism, and in certain of its important features such a mechanism especially capacitated for controlling metered electric currents; to provide an inclosed or incased and self-contained mechanism of the kind described, which does not require manual or other operation to release the mechanism or to set it going after the deposit 30 of a coin; to obviate and dispense with operating handles or equivalent mechanisms and also to avoid the necessity for providing the safeguarding mechanisms usually required to prevent improper actuation of handles and like parts; to provide within the self-contained mechanism actuating or impelling means which function in place of the customary external handle, such actuating and impelling means as at present embodied comprising a motor and a friction clutch.

35 40 45 Other objects and advantages and the means of effecting same will be pointed out in connection with the following detailed description of the preferred embodiment; the foregoing general description and the following detailed description as well being illustrative and exemplary of the invention but not restrictive thereof.

40 Referring now in detail to the embodiment of the invention illustrated by way of example in the accompanying drawing, the entire mechanism is enclosed within a casing C, and referring

for the present especially to Fig. 1, the controlled circuit is shown by wires 1 and 2 having spring contact terminals 3 and 4. Wires 1 and 2 which are part of the power line are connected in series with the meter 61' shown diagrammatically in Figure 1, to which meter are also connected in series the consumer line 61a. The circuit is made and broken at these contacts by a movable circuit closing and opening contact bridge 5, the bridge being moved to circuit closing position by 10 the deposit of a coin and to open circuit position by the meter registering the prepaid quantity of current consumed, with or without addition of basic charges such as time charges, or additional factors. As embodied, bridge 5 is mounted on 15 an arm 11 fixed on a shaft 12, journaled in the frame, and fixed near the other end of the shaft 12 is a bent stop arm 13. This stop arm cooperates with a shaft 14, journaled in the frame, this shaft being provided with detent recesses 15 and 20 16, one of which holds the bridge piece 5 at and releases it from the circuit closing position, and the other of which holds the bridge piece in open circuit position and releases it therefrom at the proper time so that it may move to circuit-closing 25 position. The shaft 14 is normally held in position to obstruct and stop the bent stop arm 13 with the switch either open or closed, and is yieldingly movable into releasing position, the means for effecting this comprising a pin 17 projecting from the shaft 14, which pin is yieldingly held in position against a detent 18 by spring 19, that is, in the position to hold bent arm 13.

30 35 40 45 Means are provided for placing impulsion on the above described mechanism so that it will move successively from circuit closing to circuit opening and to circuit closing position on successive releases thereof by the shaft 14, which mechanism is also contained within the closed casing. Suitable power supplying and friction slip clutch devices are provided within the casing, and as embodied, the power device comprises a motor 27, having a pinion 28 on its shaft, meshing with a gear 29 fixed on a shaft 30, which shaft is journaled in the machine frame. Fixed also on shaft 30 is a pinion 31, meshing with a gear 32 loose on shaft 12, and a coil spring 33 is in compression between gear 32 and bent arm 13, imposing a friction slip drive on arm 13.

50 The embodied form of coin actuated circuit closing means cooperates with the mechanism just described, and includes a coin inserting slot 39. In line with the slot and within the casing is a coin drum 40 fixed on motor driven shaft 30. The drum 40 has a central portion 41 of lesser 55

diameter, and a coin receiving slot 43, the slot being internally narrowed so that a dropped coin *c* will be received into the drum slot and held with its edge portion extending from and across the central reduced portion 41 of the drum, the coin in this position serving as an actuating device for a portion of the mechanism to be later described. Referring now to this coin actuated mechanism, a ratchet wheel 45 is fixed on a sleeve 46, which sleeve is loosely mounted on a shaft 47, journaled in the frame. The ratchet wheel 45 projects within the reduced portion 41 of the coin drum so that the ratchet wheel may be moved the distance of one tooth by a coin held in the rotating drum 40. In the actual machine the ratchet wheel 45 will be practically on the same level as the shaft 30, and the coin will drop out of the drum wheel slot by gravity after a half revolution of the drum and after having moved the ratchet wheel 45 the distance of one tooth. A detent 48 coacts with the ratchet wheel 45 to hold it except when moved by the coin. Fixed also on sleeve 46 is a sun wheel 49 of a planetary gear. A cooperating sun wheel 50 is fixed on a sleeve 51, which is loosely journaled on the shaft 47, a gear 52 being likewise fixed on sleeve 51. The planet wheel 53 is loosely mounted on an arm 54 fixed on a shaft 47. Fixed also on shaft 47 is an arm 55, which 15 acts with an arm 56 fixed on the shaft 14 to effect the operation of the switch actuating mechanism.

The current metering means as embodied likewise operates on the planetary gear and the arms 35 55 and 56 to open the circuit after a given current consumption and as embodied, a shaft 61 is driven by the meter and drives on to a gear 62, fixed on a shaft 63 journaled in the frame. Fixed also on shaft 63 is a pinion 64, which meshes with 40 a gear 65, fixed on a shaft 66, a pinion 67 being also fixed on shaft 66 and meshing with the gear 52. The coin operated mechanism acts on arm 55 and through it on bent arm 13 to move bridge 5 to close the circuit at contacts 3 and 4, and the 45 meter driven gearing acts on arm 55 and through it on bent arm 13 to permit movement of bridge 5 to open the circuit at the contacts 3 and 4.

The operation of the foregoing mechanism is as follows:

50 Let it be assumed, for example, that the supply of electricity or other commodity corresponding to the coin last deposited (which has previously fallen out of the coin slot 43 into the coin receptacle) is not yet consumed. At this time bridge piece 5 closes the circuit, and detent notch 15 holds bent arm 13 against the impulsion of the friction slip drive exerted from motor 27. Arm 55 is also spaced away from arm 56. The meter driven shaft 61 is driving gears 52 and 50 so that planet wheel 53 is rolling on sun wheel 49, and arm 55 is consequently approaching arm 56. When the coin value in electricity or other commodity is consumed, arm 55 engages arm 56 and rocks shaft 14 against the pressure of spring 19 until detent notch 15 releases the bent arm 13, and shaft 12 makes a half revolution under the impulsion of the friction slip drive, and is then stopped by arm 13 engaging detent notch 16 on shaft 14, and the mechanism is at rest in the 65 open circuit position, and shaft 61 is likewise at rest. Shaft 30 continues to rotate under the drive of motor 27.

When a coin is dropped in slot 39, it passes into drum 40, and on the first half revolution of 70 the drum moves ratchet wheel 45 the distance of

one tooth, sun wheel 49 rotating therewith and rolling planet wheel 53 on sun wheel 50 in the opposite direction from that in which it was moved by shaft 61. Arm 55 is thereby moved in the opposite direction, and arm 56 and shaft 14 5 are restored by spring 19 to their original position, shown in Fig. 1, and arm 13 is released for a half revolution and bridge piece 5 again closes the circuit at the contacts 3, 4, and the circuit will remain closed until opened again by the drive 10 from the meter in the manner already described.

An embodiment of the invention is diagrammatically illustrated in Fig. 2 of the drawing wherein a part of the value of the coin inserted is credited to a basic or fixed charge, i. e., where in current is not supplied for the full value of a coin, but in an amount less by a predetermined percentage or proportion depending upon the basic or fixed charge. In said embodiment the coin drum is actually two concentric side by side 20 drums 40^a and 40^b one-half of the coin slot being formed in the inner ends of the two drums, and when a coin is introduced through slot 39 it forms a driving connection between driving drum 40^a, which is driven from motor 27, and 25 driven drum 40^b for a half revolution, until the coin drops out by gravity. A disc 71 having two flat sides is fixed on the outer end of drum 40^b, and a flat spring 72 acts to stop drum 40^b after the half revolution just described. Drum 40^b is 30 fixed on a shaft 73 to which is fixed a pinion 74, which meshes with gear 45^a. Reference numerals 45^a to 61^a in Fig. 2 are applied to substantially the same or similar parts as are the plain numerals in Fig. 1, and these parts need not be 35 again described.

Referring now to the connections from the foregoing mechanism for operating and governing the switch controlling mechanism, a gear 81 is fixed on shaft 47^a, and meshes with a gear 82 40 fixed on a shaft 83. Fixed to the hub of gear 82 is a radially extending and angled arm 84, having fixed thereto a detent tooth 85. Loosely sleeved on shaft 83 are a pair of escapement gears 87 and 88, which are fixed together and are offset angularly half the pitch of their teeth to effect, when moved along their shaft, an escapement action with the detent 85. Fixed to the gears 87 and 88 to rotate therewith are two broad faced pinions 93 and 94, and fixed to these is a grooved and flanged wheel 95; the escapement wheels, the broad faced pinions and the grooved wheel being integral and rotating freely together on shaft 83, and being also movable along the shaft. The connections from the aforesaid mechanism to the switch controlling mechanism comprises a shaft 99, journaled in the frame, and fixed on a shaft 99 is a gear 100, which meshes with broad faced pinion 93, and fixed on the other end of shaft 99 50 is an arm 101. Arm 101 coacts with bent arm 102 on shaft 103 of the switch controlling mechanism (not shown) which may be of the form shown in the prior patent to Beusch and Pudelko, No. 1,799,276. The switch and switch operating means controlled by arms 101 and 102 may be of suitable or desired form, and may be the same or similar to those shown in Fig. 1 and previously described.

In the embodied form of mechanism for imposing the basic or other additional charge, a 70 time controlled drive for the escapement mechanism just described is provided, wherein an escapement operating shaft 108 is driven from a suitable source, which may be the motor 27 especially if it be a synchronous motor. As shown, 75

a bevel gear 109 on shaft 108 is driven from a bevel gear 110, fixed on a shaft 111, which is driven from motor shaft pinion 28 through gear train 112. The motor 27 may be a synchronous 5 motor to provide a time measurement or for any other purpose. The upper end of shaft 108 projects into the groove in the wheel 95 and is offset to give a crank motion, so that as the shaft 108 is rotated by the time mechanism, the grooved wheel 95, the broad faced pinions and the escapement wheels are reciprocated on their shaft, and by reason of the offset of the wheels by one-half of the tooth pitch, an escapement 10 action is effected in conjunction with detent 85. 15 Shaft 83 is driven from the meter, and arm 84 and detent 85 rotate about shaft 83, advancing the wheels correspondingly to the power consumed, and the rotation of shaft 108 operates the escapement, the total advance of the wheels 20 87, 88 and pinions 93, 94 being the sum of both these drives, or the sum of the current consumption plus the additional charge.

In accordance with one feature of the invention, driving means are provided for imposing a 25 resilient or yielding forward drive on the wheels 87, 88 and pinions 93, 94 whereby they move forwardly under the concurrent drive of the meter disc and under the control of the time mechanism, said driving means being independent of 30 the time mechanism. As embodied, the driving means comprises a helical spring 116 which is connected to a toothed sector 117. Sector 117 meshes with a pinion 118 fixed on a shaft 119, and a gear wheel 120 is fixed on the shaft 119 and 35 meshes with the broad pinion 94 to communicate the drive from spring 116 to the escapement mechanism, the group of mechanism which includes arm 84, gears 87, 88 and pinions 93, 94 acting to control the spring drive in accordance 40 with the movement of the meter and the time mechanism or drive from motor 27.

Referring now to the manner of operation of the embodiment shown in Fig. 2, the fundamental features of operation are the same as previously described with the addition that the mechanism for imposing the additional charge as, for instance, a time mechanism cooperates with the meter drive to advance the mechanism to open circuit position, the coin itself, as before, being employed to release the mechanism again for circuit closing position. Assuming that the supply of electricity corresponding to the coin last introduced has not been exhausted, and that the deposited coin has previously dropped out of the coin slot after a half revolution, and thereby has mechanically disconnected the two drums 40^a and 40^b, so that 40^b is brought to rest by the action of the spring 72 while 40^a continues to rotate with the motor. The meter driven shaft 61^a drives through the escapement mechanism and shaft 99 to slowly advance arm 101 to the position where it will move lever arm 102 to open the switch through the switch controlling mechanism, which if desired may be generally similar or the same as that of Fig. 1 being connected to the shaft 103. Concurrently the motor 27 is rotating crankshaft 108 to additionally advance the time escapement, the advancement of the arm 102 towards switch opening position being the sum of these two drives. If the time charge or other basic charge is supplied only during current consumption, a control switch on the motor 27 may be provided, and such a switch may be supplied for the motor 27 to meet any other operating condition as found convenient or desirable.

If desired, a time control may be provided for the motor 27 to govern its operation in any way desired. When a new coin is inserted, it drops into the slots in the drums 40^a and 40^b, thereby mechanically connecting them and they rotate 5 together for a half revolution when the coin drops out, and drum 40^b comes to rest. During that half revolution, pinion 74 rotates sun wheel 49^a, causing planet wheel 53^a to roll on sun wheel 50^a in the opposite direction from its movement 10 during the current flow, thereby rotating the entire escapement mechanism backwardly, winding spring 116 and moving arm 101 backwardly 15 from arm 102 so that spring 19, or equivalent device, will close the supply switch and start the current flowing. The operation of the mechanism due to the supply of a coin being the same as that previously described in connection with the mechanism of Fig. 1.

The invention in its broader aspects is not limited to the specific mechanisms shown and described but departures may be made therefrom within the scope of the accompanying claims without departing from the principles of the invention and without sacrificing its chief advantages.

What I claim is:

1. A coin controlled electricity measuring mechanism enclosed within a casing and including in combination a switch, a meter-operated shaft, 30 means including a slip drive impelling the switch to continuous movement to successive open circuit and closed circuit positions, means restraining the operation of said impelling means, means operated by the meter operated shaft after a pre- 35 determined current consumption for releasing said restraining means to cause the switch to open, and a power device located within the casing and called into operation by an inserted coin for releasing said restraining means to cause the 40 switch to close.

2. A coin controlled electricity measuring mechanism enclosed within a casing and including in combination a switch, a meter-operated shaft, means including a slip drive impelling the 45 switch to continuous movement to successive open circuit and closed circuit positions, means restraining the operation of said impelling means, means operated by the meter operated shaft after a predetermined current consumption for releas- 50 ing said restraining means to cause the switch to open, and a power device located within the casing and called into operation by an inserted coin for releasing said restraining means to cause the 55 switch to close, said slip drive comprising driven and driving members, the driven member being connected to said impelling means, and said power device being connected to said driving member.

3. A coin controlled electricity measuring 60 mechanism enclosed within a casing and includ- ing in combination a movable switch operating member, a switch adapted to be successively closed and opened by said switch operating mem- 65 ber, means including a continuously moving pow- er device and a slip clutch adapted to impel the switch operating member to continuous move- ment in a single direction to successively close and open said switch, movable means associated with said impelling means normally restraining 70 the operation thereof, means holding said mov- able means in restraining position, said impelling means including a coin receptacle and means to discharge said coin, means associated with said holding means and adapted to be actuated by a 75

coin in said receptacle for operating said holding means to release the releasing means and permit the impelling means to move said movable switch operating member to close the switch, said coin receptacle being constructed to permit ejection of said coin following this operation, a consumer circuit and a meter in series therewith, a shaft operated by said meter, and means operated by said shaft and associated with said holding means

5 to restore the same to holding position after a predetermined current consumption measured by the duration of operation of the meter shaft.

4. A coin controlled electricity measuring mechanism enclosed within a casing and including in combination a movable switch operating member, a switch adapted to be successively closed and opened by said switch operating member, means including a continuously moving power device and a slip clutch adapted to impel the switch operating member to continuous movement in a single direction to successively close

15

and open said switch, movable means associated with said impelling means normally restraining the operation thereof, means holding said movable means in restraining position, said impelling means including a coin receptacle which, 5 when in upright position, is adapted to receive a coin and when in inverted position to discharge the coin, means associated with said holding means and adapted to be actuated by a coin in said receptacle prior to being discharged therefrom for operating said holding means to release the releasing means and permit the impelling means to move said movable switch operating member to close the switch, a consumer circuit and a meter in series therewith, a shaft operated 15 by said meter and means operated by said shaft and associated with said holding means to restore the same to holding position after a predetermined current consumption measured by the duration of operation of said meter shaft. 20

RICCARD PUDELKO.
